UNITED STATES PATENT OFFICE.

FREDERICK W. SAUER, OF BROOKLYN, NEW YORK, ASSIGNOR TO HOME DEVICES CORPORATION, OF BROOKLYN, NEW YORK, A CORPORATION.

DOMESTIC WASHING-MACHINE.

1,202,900.

Specification of Letters Patent.

Patented Oct. 31, 1916.

Application filed December 15, 1915. Serial No. 66,903.

To all whom it may concern:

Be it known that I, FREDERICK W. SAUER, a citizen of the United States, residing in the borough of Brooklyn, county of Kings, 5 and State of New York, have invented new and useful Improvements in Domestic Washing-Machines, of which the following is a specification.

The invention relates to domestic washing machines of the type wherein a perforated clothes cylinder is suspended rotatably within a tub, and comprises certain improvements relating to the means for supporting and driving the cylinder, having for their 10 objects to secure an especially simple, strong and inexpensive construction, to provide advantageously for adjustment of the cylinder-supporting means relatively to the tub, and to improve the manner of mounting the 15 cylinder journals in the hangers. The features and combinations wherein these ends are attained will now be briefly described and more particularly pointed out in the appended claims.

In the drawings: Figure 1 is a plan view 25 of a machine embodying the invention; Fig. 2 is a side elevation thereof; Fig. 3 is a fragmentary perspective view of one end of the supporting structure; Fig. 4 is a fragmentary plan view of the opposite end of the supporting structure; Fig. 5 is a cross-section 30 on the line 5—5 of Fig. 4; Fig. 6 is a fragmentary view, partly in vertical section and partly in elevation, showing one of the 35 hangers and a cylinder journal engaged therewith; and Fig. 7 is a partial end elevation of parts shown in Fig. 6.

The tub 1 may be of various suitable characters, but is shown as circular in form, with 40 flaring sides. In it a perforated clothes cylinder 2 is rotatably supported. The primary elements for supporting the cylinder from the tub comprise two arched or angularly upbent bridge members 3 and 3^a, the terminal feet of which are provided with apertures 4 to receive studs 5 projecting upward from tub-engaging clamps 6, to which the bridge members are secured by the nuts 7.

The bridge member 3 has a flat central 50 portion 8, on top of which a plate 9 is secured, as by means of rivets 10. The said plate has parallel guide ribs 11 forced up from its body, adjacent its opposite ends. The said ribs may be formed as indicated 55 at 11^a in Fig. 5 by severing strips from the

body of the plate and bending them upward, the ends of the strips remaining integrally united. The ribs 11 of the bridge member 3 constitute lateral supports and guides for a horizontally disposed arm 12, forming a lateral extension at the top of a depending hanger 13, the said arm 12 being formed with a longitudinal slot 14, which accommodates a stud 15 rising from the central portion of the bridge member to receive a wing nut 16, by which the arm 12 may be firmly held at the desired degree of in or out adjustment.

The other bridge member 3^a has a plate 12^a riveted to its flat central portion 8^a, this 70 plate constituting a horizontal upper arm of a hanger 13^a. The said hanger arm has parallel ribs 11^a, between which a journal bearing 17 is supported, being preferably held in place by the same rivets 10^a which 75 unite the hanger arm 12^a to the bridge member. The journal bearing comprises a lower half 18 and an upper hinged half 19, the hinge being indicated at 20. At the opposite side of the bearing from the hinge the members 18 and 19 are slotted, as shown at 21, in order to accommodate a pivot bolt 22 having a wing nut 23 which clamps the upper half 80 of the bearing upon a bushing 24. In this bushing turns a shaft 25, which at its inner 85 end bears a pinion 26 meshing with a gear 27 on the cylinder and at its opposite end is provided with a handle crank 28, and said bushing 24 forms a stop to keep the pinion 26 in position.

The lower portions of the hangers 13 and 13^a are offset inwardly, as shown at 29 in Fig. 6 and are formed with bearing slots 30 for the reception of the shanks of headed journals 31 on the ends of the cylinder. The 95 offset portions 29 are connected with the bodies of the hangers by offsetting portions 32, which are preferably inclined as shown, and these offsetting portions are provided with widened extensions 33 of the slots 30. 100 As a result of this construction the cylinder journals are easily seated in their bearings by merely lowering the cylinder in the tub, and due to the shape of said slots 30 it is impossible for the cylinder to slip out of 105 place after being set in position.

What I claim as new is:

1. The combination with a tub and cylinder, of means for supporting one end of said cylinder, comprising a bridge member dis- 110

posed tangentially of the rim of the tub and having a raised central portion and terminal feet, clamps securing said feet to the edge of the tub, and a hanger comprising a depending portion provided with a bearing for the cylinder and a horizontal top portion disposed crosswise of and secured to the central portion of said bridge member.

2. In a washing machine, the combination 10 with a cylinder having a headed journal, of a hanger having supporting means at the top and comprising a depending strap hav-

ing its lower end portion offset inwardly and provided with a slot serving as a bearing for said journal and an offsetting portion having a widened extension of said slot to permit the passage of the head of the journal.

15

Dated, November 30th, 1915.

FREDERICK W. SAUER.
